US0D1084060S

(12) **United States Design Patent** (10) **Patent No.:** **US D1,084,060 S**
(45) **Date of Patent:** **** Jul. 15, 2025**

(54) **REFRIGERATOR**

- (71) Applicant: **Samsung Electronics Co., Ltd.**, Suwon-si (KR)
- (72) Inventors: **Sungsu Park**, Suwon-si (KR); **Kisang Yoon**, Suwon-si (KR); **Honguk Lee**, Suwon-si (KR); **Bokyong Lee**, Suwon-si (KR)
- (73) Assignee: **SAMSUNG ELECTRONICS CO., LTD.**, Gyeonggi-Do (KR)
- (**) Term: **15 Years**
- (21) Appl. No.: **29/907,187**
- (22) Filed: **Jan. 4, 2024**

(30) **Foreign Application Priority Data**

- Sep. 25, 2023 (KR) 30-2023-0037966

(57) **CLAIM**

The ornamental design for a refrigerator, as shown and described.

DESCRIPTION

FIG. 1 is a front perspective view of a refrigerator, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 2;

FIG. 10 is an enlarged view of the encircled portion 10 in FIG. 4; and,

FIG. 11 is an enlarged view of the encircled portion 11 in FIG. 6.

The evenly dashed broken lines in the figures depict environmental subject matter and form no part of the claimed design. The dot-dash broken lines encircling portions of the claimed design that are illustrated in enlargements form no part of the claimed design.

1 Claim, 11 Drawing Sheets
